UNITED STATES PATENT OFFICE

JENNIE CALDARELLA, OF JACKSON HEIGHTS, NEW YORK

DESIGN FOR AN ENSEMBLE DRESS

Application filed December 28, 1931. Serial No. 42,268. Term of patent 3½ years.

To all whom it may concern:

Be it known that I, JENNIE CALDARELLA, a citizen of the United States, and a resident of Jackson Heights, in the county of Queens and State of New York, have invented the new, original, and ornamental Design for an Ensemble Dress, of which the following is a specification.

Reference is had to the accompanying drawings, forming part thereof, wherein—

Fig. 3 is a rear perspective view of the dress section shown in Figure 2.

I claim:

The ornamental design for an ensemble dress substantially as shown.

JENNIE CALDARELLA.
